UNITED STATES PATENT OFFICE.

ARTHUR J. BAKER, OF TOLEDO, OHIO, ASSIGNOR TO THE WILLYS-OVERLAND COMPANY, OF TOLEDO, OHIO, A CORPORATION OF OHIO.

INTERNAL COMBUSTION ENGINE.

Application filed December 17, 1923. Serial No. 681,167.

My invention relates to internal combustion engines of the sleeve valve type, and has for one of its objects, to reduce the cost of construction and operation of engines of 5 this class.

These and other objects are accomplished by removing a considerable portion of the wall of the outer sleeve and substituting therefor, a rigid bearing between the wall of 10 the cylinder and inner sleeve, at a point opposite the connecting rod pin, whereby a rigid bearing is also provided for the piston moving within the sleeve, thus tending to prevent vibration in the engine, due in part, 15 at least, to the lateral thrust of the piston and the operating parts therefor.

Further objects accomplished by eliminating a considerable portion of the outer sleeve, include the reduction of the reciprocating weight and hence, lessening of engine vibration, a decrease in the frictional resistance offered by the contacting surfaces of the parts affected, and the reduction of 20 the area upon which the oil film forms between the cylinder block and the outer sleeve, thus improving the cooling conditions under which the engine operates.

Other objects, and objects relating to the details of construction and economies of 30 manufacture, will appear from the description to follow, covering that embodiment of the invention, which, for the purposes of the present application, I have illustrated in the accompanying drawings, in which:

Figure I is a transverse sectional elevation through an engine embodying the invention.

Fig. II is a sectional plan on an enlarged scale, taken on line II-II of Fig. I.

Fig. III is a side elevation of the outer sleeve shown removed from the cylinder, and

Fig. IV is a sectional plan taken on line IV-IV of Fig. III.

The objects pointed out above are accomplished by designing the outer sleeve in such a manner as to greatly reduce the contacting surfaces of the sleeves, one upon another, and of the outer sleeve upon the cylinder block, preferably by forming the outer sleeve with a valve portion of substantially no greater length than is required to afford the proper amount of material on the opposite sides of the inlet and exhaust ports. This relatively short sleeve valve is provided 55 with an operating extension and steadyng

or guiding member, preferably semi-circular in cross section, projecting downwardly through the cylinder. However, the extent to which it is projected around the inner sleeve, and its shape as well, may be varied 60 if desired. With the arrangement shown, both the frictional resistance offered to the movement of the valves, and the amount of material used in their construction, is considerably reduced and therefore a saving 65 both in the first cost, and the cost of upkeep, is effected, along with the improvements in operating conditions set forth above.

In the drawings I have shown an engine 70 frame or base 10 carrying a cylinder block 11, which is secured upon the frame in the usual manner. The cylinder head and junk rings are omitted, their construction preferably being the same as that used in the 75 well-known Knight sleeve valve engine. The cylinder is provided with inner and outer sleeve valves 12 and 13 respectively, having the usual intake and exhaust ports adapted for communication with the corre- 80 sponding ports in the walls of the cylinder, all of which is of well-known construction.

A piston 14 of any suitable type is mounted within the sleeves and actuated by the connecting rod 15 on the crank-shaft 16. 85 The outer sleeve 13 is provided with a downwardly projecting operating extension 17, which is preferably semi-circular in cross-section, as shown in Fig. IV. The extension 17 is provided with a bifurcated arm 18 90 operatively connected with the eccentric shaft 19 by a link 20 and pin 21, as shown in Fig. I. Likewise, the inner sleeve 12 is provided with a similar arm 22 operatively connected with the eccentric shaft by the 95 link 23 and pin 24.

From the construction shown, it will be seen that the outer sleeve proper is something less than half the length of the inner sleeve, and that the amount of material discarded is approximately equal to one-fourth of that heretofore used in sleeve valves of this type.

Since so large a portion of the outer sleeve is cut away, it is necessary to provide a bearing for the left hand side of the inner sleeve, as indicated at 25 in Fig. I. This bearing is provided with a circular flange 26 secured to the cylinder by suitable bolts 27, as shown in Figs. I and II. The bearing 105 110

is mounted opposite the connecting rod pins and extended below the cylinder a considerable distance in order to take the lateral thrust on the inner sleeve produced by the connecting rods of either sleeve, or by the movement of the piston when nearing the end of its downward stroke. The bearing is made removable so that should it become excessively worn, it can be readily taken out and replaced by a new one. It is preferably constructed to occupy something less than half the space produced by the cutting away of the outer sleeve in the manner shown.

15 Both the inner and outer sleeves are preferably additionally lightened through the removal of a considerable portion of the material, by the drilling or otherwise forming of a series of holes 28 and 29 therein, 20 as shown in Fig. I.

Oil grooves 30 and 31 are formed within the outer and inner lower sleeve portions respectively, as shown in Fig. I, and one or more diagonally arranged oil grooves 32 25 are provided within the valve portion 13 of the outer sleeve.

While I have shown in considerable detail, a specific embodiment of my invention, it is to be understood that this showing and 30 description are illustrative only, and that I do not regard the invention as limited to the details of construction illustrated and described, except in so far as I have included such limitations within the terms of the 35 following claims, in which it is my intention to claim all novelty inherent in my invention broadly, as well as specifically.

I claim as my invention:

1. In an internal combustion engine, a cylinder, inner and outer sleeve valves therein, the latter encircling the former at its upper end and having a reduced extension projecting downwardly within the cylinder, said extension being of a length as great as the 45 length of the encircling portion, a bearing member for said inner sleeve fixed to said cylinder diametrically opposite to said outer sleeve extension, and driving means operatively connected with said inner sleeve and with the extension of the outer sleeve.

2. In an internal combustion engine, a cylinder, inner and outer sleeve valves therein, the latter encircling the former at its upper end and having a reduced extension projecting downwardly within the cylinder and through the lower end thereof, said extension being of a length at least as great as the length of the encircling portion, a piston 60 operable within the valves, a member fixed to said cylinder below said outer sleeve encircling portion and contacting with the inner sleeve, and driving means operatively connected with said piston and valves.

3. In an internal combustion engine, a cylinder, inner and outer sleeve valves therein,

the latter encircling the former at its upper end and having an extension within the cylinder of less cross-sectional area than said encircling portion, said extension forming with said cylinder an arcuate space therebetween, 70 a member within said space fixed to said cylinder and contacting with said inner sleeve, said member being adapted to permit movement of both of said sleeves, and driving means operatively connected to the 75 valves.

4. In an internal combustion engine, a cylinder, inner and outer sleeve valves therein, the outer one of which is cut away at points within the cylinder to lessen weight 80 and reduce the frictional resistance caused by the sliding of the sleeves upon each other, a bearing member between the inner sleeve and the cylinder, having less surface area than said cut-away portion, and driving 85 means operatively connected with said valves.

5. In an internal combustion engine, a cylinder, inner and outer sleeve valves therein, the outer sleeve being cut away at points 90 within the cylinder to reduce the frictional resistance caused by the sliding of the sleeves upon each other, a bearing member between the inner sleeve and the cylinder, means for removably securing said bearing member in 95 position, and driving means operatively connected with said sleeve.

6. In an internal combustion engine, a cylinder, inner and outer sleeve valves therein, the latter being cut away for a portion 100 of its length within the cylinder, a bearing between the cylinder and inner sleeve upon which the latter is adapted to slide, and driving means operatively connected with said sleeves.

7. In an internal combustion engine, a cylinder, inner and outer sleeve valves therein, the latter encircling the former at its upper end and having a downwardly projecting extension of less cross-sectional area 110 than said encircling portion, a bearing member positioned below said encircling sleeve portion and between the cylinder and the inner sleeve, and driving means operatively connected with said sleeves.

8. In an internal combustion engine, a cylinder, a piston therein, a sleeve valve between the cylinder and piston having an upper circular portion and a lower cut away portion of less than circular extent, and a fixed abutment having an inner bearing surface of the same cylindrical contour as the inner side of said sleeve, said fixed abutment occupying part of the space left free by said cut-away portion.

9. In an internal combustion engine, a cylinder, inner and outer sleeve valves therein projecting below the bottom of the cylinder and each having an operating arm thereon, one of said sleeves having its wall cut 130

away for a considerable portion of its length above the bottom of the cylinder, and driving means operatively connected with said arms.

5 10. In an internal combustion engine, a cylinder, a piston therein, inner and outer sleeve valves between the piston and cylinder, one encircling the piston for a portion of its length and having a reduced extension 10 for the remaining and greater portion of its length within the cylinder, means fixed to said cylinder for supporting the lower portion of said inner sleeve in movable relation to said cylinder and driving means opera-

tively connected with said piston and said 15 valves.

11. In an internal combustion engine, a cylinder, inner and outer sleeve valves therein, the latter having a reduced extension for the lower portion of its length, whereby a 20 space is afforded between the cylinder and inner sleeve, a bearing positioned between said cylinder and the inner sleeve and adapted to fill a portion of said space, and driving means operatively connected with said piston and said sleeves. 25

In testimony whereof, I affix my signature.

ARTHUR J. BAKER.
